(57) **CLAIM**

The ornamental design for a “set of chess pieces,” as shown and described.

DESCRIPTION

FIG. 1 is a perspective view showing the set of chess pieces with known repetitive pieces removed in their environment;
FIG. 2 is a perspective view of the king chess piece of the present invention;

FIG. 3 is a right or left side view of the king chess piece of the present invention;

FIG. 4 is a front or back view of the king chess piece of the present invention;

FIG. 5 is a top end view of the king chess piece of the present invention;

FIG. 6 is a bottom end view of the king chess piece of the present invention;

FIG. 7 is a perspective view of the queen chess piece of the present invention;

FIG. 8 is a right or left side view of the queen chess piece of the present invention;

FIG. 9 is a front or back view of the queen chess piece of the present invention;

FIG. 10 is a top end view of the queen chess piece of the present invention;

FIG. 11 is a bottom end view of the queen chess piece of the present invention;

FIG. 12 is a perspective view of the bishop chess piece of the present invention;

FIG. 13 is a right or left side view of the bishop chess piece of the present invention;

FIG. 14 is a front or back view of the bishop chess piece of the present invention;

FIG. 15 is a top end view of the bishop chess piece of the present invention;

FIG. 16 is a bottom end view of the bishop chess piece of the present invention;

FIG. 17 is a perspective view of the knight chess piece of the present invention;

FIG. 18 is a left side view of the knight chess piece of the present invention;

FIG. 19 is a front view of the knight chess piece of the present invention;

FIG. 20 is a right side view of the knight chess piece of the present invention;

FIG. 21 is a back view of the knight chess piece of the present invention;

FIG. 22 is a top end view of the knight chess piece of the present invention;

FIG. 23 is a bottom end view of the knight piece of the present invention;

FIG. 24 is a perspective view of the rook chess piece of the present invention;

FIG. 25 is a right or left side view of the rook chess piece of the present invention;

FIG. 26 is a front or back view of the rook chess piece of the present invention;

FIG. 27 is a top end view of the rook chess piece of the present invention;

FIG. 28 is a bottom end view of the rook chess piece of the present invention;

FIG. 29 is a perspective view of the pawn chess piece of the present invention;

FIG. 30 is a right or left side view of the pawn chess piece of the present invention;

FIG. 31 is a front or back view of the pawn chess piece of the present invention;

FIG. 32 is a top end view of the pawn chess piece of the present invention; and,

FIG. 33 is a bottom end view of the pawn chess piece of the present invention.

The dashed lines in FIG. 1 show the environment of and form no part of the present invention. The invention is as shown and described in the accompanying figures.
